US0D1042145S

(12) **United States Design Patent** (10) Patent No.: **US D1,042,145 S**
(45) Date of Patent: ** Sep. 17, 2024

(54) **BOTTLE**

(71) Applicant: **Conopco Inc.**, Englewood Cliffs, NJ (US)

(72) Inventors: **Christopher Paul Weir**, Wirral (GB); **Natascha Diwani Hansen**, Wirral (GB); **Jamie Mark King**, Wirral (GB); **Jessica Frances Sophia Peake**, Wirral (GB)

(73) Assignee: **Conopco Inc.**, Englewood Cliffs, NJ (US)

(**) Term: **15 Years**

(21) Appl. No.: **29/926,785**

(22) Filed: **Feb. 1, 2024**

Related U.S. Application Data

(60) Division of application No. 29/796,397, filed on Jun. 24, 2021, which is a continuation of application No. 29/763,813, filed on Dec. 24, 2020, now Pat. No. Des. 991,039.

(57) **CLAIM**

The ornamental design for a bottle, as shown and described.

DESCRIPTION

FIG. 1 is a perspective view of a bottle according to our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines, the areas within them, and the unshaded areas bounded by broken lines and solid lines depict portions of the bottle that form no part of the claimed design.

1 Claim, 7 Drawing Sheets
